UNITED STATES PATENT OFFICE

JAMES S. WILEY, OF NEW YORK, N. Y., ASSIGNOR TO KAEELMA MANUFACTURING COMPANY, INC., OF NEW YORK, N. Y., A CORPORATION OF NEW YORK

BAG OR ENVELOPE

Application filed December 3, 1926. Serial No. 152,406.

This invention relates to improvements in handled bags or envelopes, and has particular reference to improved locking means for such devices.

5 An important object of the invention is to provide a bag or envelope with a closure flap and means for interlocking the two walls when the flap is closed.

Another object is to provide such a device 10 wherein the interlocking of the two walls is accomplished by the closing movement of the flap.

Another object is to provide such a device 15 with a handle member to facilitate closing the flap and carrying the bag, said handle member cooperating with the wall interlocking means to hold the mouth of the bag closed.

With these and other objects in view, the 20 invention resides in the novel features of construction and arrangement of parts hereinafter set forth, shown by way of illustration in the accompanying drawings, and specifically pointed out in the appended claims.

25 In the drawings, Figure 1 is a rear elevation of one form of handled envelope or bag embodying the invention, and showing the parts in open position;

Fig. 2 is a vertical transverse sectional view 30 on line 2—2 of Fig. 1;

Fig. 3 is a fragmentary view similar to Fig. 1 illustrating the position of the parts prior to closing the flap;

Fig. 4 is a transverse sectional view on 35 line 4—4 of Fig. 3;

Fig. 5 is a transverse sectional view showing an intermediate stage in the closing of the flap;

Fig. 6 is a fragmentary rear elevation of 40 the bag in closed condition;

Fig. 7 is a transverse sectional view therethrough; and

Fig. 8 is a fragmentary front elevation of the bag as shown in Figs. 6 and 7.

45 As shown in Figures 1 and 2, the bag or envelope has a pair of opposed walls 10 and 11, and a closure flap 12 carried by the wall 11 and foldable to overlie a portion of the wall 10. A handle 13, formed of sheet material such as cardboard or the like, has a body

portion 14 secured to the inner surface of the flap 12 by gum, paste or other suitable means. The free end 15 of the handle 13 extends over the fold line of the flap and outwardly through a slit 16 in the wall 11, and may preferably be provided with a finger hole 17 suitably proportioned to accommodate one or more fingers for carrying the bag. The free end 15 of the handle is preferably narrower than the body portion 14, whereby to provide 55 shoulders 18 toward the handle proper, and the side edges of the handle are flared out slightly as at 19 adjacent said shoulders. The slit 16 is preferably of such a length that its ends are in line with the edge portions 19 60 of the handle, and from this it will be evident that outward movement of the handle through the wall 11 will be limited by the shoulders 18. If desired, a reinforcing patch 20 may be secured to the wall 11 in the vicinity of the slit 16, said patch being similarly 65 slotted, and being secured as by gum, paste, or the like, to either the inner or outer surface of the wall 11.

The open or upper edge of the wall 10 may 75 be provided with a pair of inwardly extending notches 21, 21, the outer edges 22 of which are preferably in line with the ends of the slit 16 and the edges 19 of the handle. The inner edges 23 of the notches define between them a tongue 24 which extends freely 80 beyond the edge of the wall 10 and beyond the fold line of the flap 12.

The normal disposition of the flap, tongue, and handle when the bag is open is shown in 85 Figs. 1 and 2, from which it will be evident that in this condition the open end of the bag is unobstructed, permitting insertion of any desired articles within the bag body. After such insertion, the free end of the tongue 24 90 is slipped through the opening or hole 17 to a position between the handle 13 and the inner surface of the flap 12 as shown in Figs. 3 and 4. Thereafter the bag may be closed by moving the flap 12 through the instrumentality of the handle as shown in Fig. 5. As the closing movement of the flap continues, the handle 13 moves outwardly through the slit 16, at the same time folding the tongue 24 95 at 25 and drawing said folded portion 100

through the slit. The movement continues until the flap reaches its closed position at which time the shoulders 18 engage the bag material at the ends of the slit 16, and the free end 15 of the handle extends upwardly beyond the fold line. In this condition the shoulders 18 extend over the edges 22 causing mutual engagement between the walls 10 and 11, and the extremity of the tongue 24 is reversely folded to extend inwardly through the slot at the opposite side of the handle. As the bag with its contents is held by the handle, its weight imposes a clamping pressure on the opposed walls through the shoulders 18, and also on the folded tongue 24. Thus the walls are firmly locked together, the interlocking of the tongue with the wall 11 having been effected by the closing movement of the flap.

By way of assisting in locking the bag in closed position, the handle 14 may be provided with projecting portions 26 forming lateral shoulders 27. These projecting portions are preferably tapered whereby to be capable of freely passing through the slit 16, the shoulders 27 coming to rest just beyond the slit as shown in Fig. 8, preventing accidental opening of the flap. The projecting portions 26, per se, are not novel parts of the present invention, and therefore more detailed description of them is omitted.

It will be evident from the foregoing that an improved bag or envelope has been provided with effective means for interlocking the walls in closing the bag. The construction is extremely simple, rendering it capable of economical manufacture, and exceptionally convenient for packing, closing, and carrying merchandise and the like. Obviously the invention is susceptible of numerous modifications in the details of construction and arrangements of parts, and the right is herein reserved to make such changes as fall within the scope of the appended claims without departing from the spirit of the invention.

Having thus described my invention, what I claim is:

1. In a bag or envelope, the combination of the bag body having a pair of opposed walls, a closure flap, closing means adapted to be moved outwardly through one of said walls and operable on the flap to close it, and means on the other wall for interlocking engagement with the first mentioned wall and the closure means when the flap is closed.

2. In a bag or envelope, the combination of the bag body having a pair of opposed walls, a closure flap on one wall, said wall being provided with a transverse slit spaced from and parallel with the fold line of the flap, a tongue extending from the other wall, and means on the flap for automatically projecting the tongue through said slit as the flap is closed.

3. In a bag or envelope, the combination

of the bag body having a pair of opposed walls, a closure flap on one wall, said wall being provided with a transverse slit spaced from and parallel with the fold line of the flap, a tongue extending from the other wall, and closing means adapted to be moved outwardly through said slit and operable on the flap to close it, said closing means being adapted to project said tongue through the slit as the flap is closed.

4. In a bag or envelope, a body portion having front and back walls, a closure flap, a handle secured to the closure flap and, when the flap is open, extending through the front wall and movable therethrough to close the flap, and a locking tongue on the back wall adapted to be carried through said front wall by the flap-carrying movement of the handle.

JAMES S. WILEY.
